Int. Cl. D12—14

U.S. Cl. D90—20

FIG. 1

FIG. 2

FIG. 3

FIG. 1 is a perspective view of a tire showing my new design, the section shown being repeated around the circumference of the tire;

FIG. 2 is a fragmentary plan view of a section of the tread of the tire shown in FIG. 1; and

FIG. 3 is a transverse sectional view through the tire substantially on the plane indicated by the line 3-3 of FIG. 2.

The dominant features of the design are shown in full lines;

I claim:

The ornamental design for a tire, substantially as shown and described.
